BIPARTING ELEVATOR DOOR INTERLOCK

Nicholas R. Guilbert, Jr., Chestnut Hill, Pa.

Application May 7, 1949, Serial No. 91,949

15 Claims. (Cl. 187—57)

1

This invention relates to door locks, particularly to a safety lock for a biparting freight elevator door or the like for preventing operation of the elevator when the door is open as well as for preventing the opening of the door except when the elevator is stopped at or substantially at the floor level.

There have been proposed many types of so called door interlocks adapted for use in connection with elevator doors of various kinds, and some have been reasonably satisfactory under normal conditions. When subjected to tampering, however, they may permit the elevator to be operated while the doors are open, or the doors to be unlocked and opened when the elevator is at some other floor, either of which possibilities may result in personal injury or loss of life as well as damage to property and equipment.

It is therefore a principal object of the invention to provide an interlock for biparting elevator doors which conforms to or exceeds existing safety standards and which affords maximum security of person and property, even against efforts to jeopardize this security by tampering with the equipment.

Another object is to provide elevator door interlocking mechanism which is effective to securely lock the door panels at a floor entrance to the hatchway, to prevent the elevator being moved from the floor level until the panels have been so locked, and to prevent the doors from being opened except while the elevator is at the floor level with its driving motor deenergized.

Other objects, purposes and advantages of the invention will hereafter more fully appear or will be understood from the following description of a preferred and a modified embodiment of it wherein reference will be had to the accompanying drawing in which:

Fig. 1 is a fragmentary view in elevation from within the elevator hatchway of the elevator door interlocking mechanism in operative relation with vertically slidable panels of a biparting elevator door of which but fragmentary parts are shown in association with a guide rail of conventional form.

Fig. 2 is a side elevation of the mechanism shown in Fig. 1, with the door panels, as in Fig. 1, closed and locked.

Fig. 3 is a view similar to Fig. 2 but with the door panels open.

Referring now more particularly to the drawing it will be understood the door panels P, P', guide shoes S, S' respectively attached to them, and the guide rail R which by engagement with

2

the shoes maintains the panels in approximate alignment for parallel movement away from and toward each other to open and close the hatchway entrance may be of any suitable kind or character and form no part of the invention, as the door interlock with which the latter is directly concerned may be readily adapted for effective operation in association and combination with substantially any biparting doors or other oppositely reciprocal elements, or in some instances may be employed in connection with but a single door panel or other element in which case one of the locking members may be omitted. It will be further understood the interlock as specifically illustrated is designed for employment in connection with an electrically controlled elevator provided with an element known in the art as a "retiring" cam carried by the elevator and adapted to be projected outwardly therefrom toward the adjacent hatch wall upon deenergization of the elevator driving circuit to stop the elevator and to be retracted preparatory to moving the elevator to another floor, although in a modification hereafter to be described the interlock may readily be adapted for use in association with a "stationary" cam on the elevator.

Thus in its preferred embodiment the interlock as shown in the drawing is positioned adjacent the guide rail R and includes elements adapted respectively to engage a wing arm W on lower door panel P and lock bracket L on the upper panel P' to lock the panels in place when the doors are closed. The first of these elements, the lower latch arm 1, is pivoted in an interlock housing 2 on a transverse pivot pin 3 for oscillatory movement into and out of the path of the wing arm W on panel P while an upper latch arm 4, pivoted for movement about the same axis is movable into and out of the path of lock bracket L on panel P'; if desired springs, not shown, may be provided for urging the latch arms 1 and 4 toward their locking positions illustrated in Fig. 2 as is customary in many types of door locking devices.

The upper latch arm 4 is provided with an angularly projecting roller arm 5 carrying a roller 6, the position of which is desirably adjustable through the medium of a bolt 7 and nut 8 to enable the roller to be set at the appropriate position for proper engagement by the retiring or stationary cam carried by the elevator so that when the latter stops at a floor the roller and hence the upper latch arm is moved thereby about the axis of pivot pin 3 from "locked" position (Fig. 2) to "unlocked" position (Fig. 3).

The lower latch arm 1 is provided with a bevel face 10 adapted for engagement by a striker cam 11 carried by the lower panel P and provided with any suitable mechanical or manual operating means for swinging it into engagement with the latch to move the latter out of the path of the wing arm W when the door is to be opened. Thus it is apparent that when the door panels are closed, and with the latch arms in the positions illustrated in Fig. 2 the doors cannot be opened unless the latch arms are first moved out of the paths respectively of the lock bracket L and wing arm W. Normally these latch arms are moved respectively by the elevator cam (not shown) and striker cam 11, the panels usually being counterbalanced and so interconnected that when both are free to move either will move in response to movement of the other.

The lower latch arm 1 however cannot be swung on its pivot to unlock the lower panel, either by operation of the striker cam or otherwise, unless the upper latch arm 4 has first been retracted since arm 4 comprises an integral projecting arm 12 within the housing 2 which pivotally supports a depending tumbler 13 having an inclined locking face 14 adapted for engagement by the complementary face 15 of an integral dog 16 on the lower latch arm 1 thus inhibiting movement of the latter when the parts are in locked (Fig. 2) position. The tumbler 13 is provided with a slot 17 through which a pin 18 extends into a boss 19 on the inner face of the housing 2 whereby the tumbler can move freely substantially parallel to the inner face of the housing but is prevented by the pin and boss from being swung about its pivot by the dog 16 on the lower latch arm.

There is also provided an electrical circuit interlock whereby the main elevator motor driving circuit is held open when the latch arms are retracted, this circuit including a contact unit 20 containing a switch of any suitable type connected in the motor control circuit in the usual way and provided with an operating arm 21 adapted for actuation by a contact control fork 22 which, when the elevator is provided with a retiring cam, is desirably integral with or relatively immovable with respect to roller arm 5 for movement therewith to open said circuit when the roller arm is actuated by the retiring cam. When the elevator is provided with a stationary cam however, it may be preferable to form the contact control fork 22 integral with or to secure it to the lower latch arm 1 and to rearrange the action of the switch in contact unit 20 so the main circuit is interrupted by opening of the switch when lower latch arm 1 is actuated, instead of being interrupted upon actuation of the roller arm 5. It nevertheless is but a matter of choice, depending on conditions, which of the said arms is instrumental in actuating the contact control fork provided the latter be arranged for positive actuation by one of them and moves correspondingly therewith to actuate the switch arm 21 to open and close the contact unit switch, and it will therefore be evident the interlock may be used equally well in association with an elevator provided with a retiring cam or with one having a correspondingly positioned stationary cam.

As an additional safety measure my interlock includes further mechanical means for preventing tampering with the contact unit control to permit operation of the elevator while the doors are open, said means being fully effective to produce this result under normal conditions but also proof against improper efforts to prevent their own normal operation. For this purpose there is pivoted

in the housing 2 on a pivot pin 25 a rocker 26 having one arm 27 disposed for engagement by the upper edge of wing arm W to swing the rocker clockwise in Fig. 2 as the door closes, a dog 28 carried by the arm and adapted to abut the inner wall of housing 2 limiting movement of the rocker in this direction, and a second arm 29 disposed for engagement by the lower edge of wing arm W to swing the rocker in the opposite direction as the door is being opened. The arm 29 contacts a pin 30 projecting from the lower latch arm 1 when moved in the latter direction, whereby the latch is held retracted by the rocker after the door has been opened, and to prevent reverse movement of the rocker while the door remains open there is pivoted to the lower end of arm 29 one end of a holding bar 31 the other end of which is pivotally supported on a link 32 pivoted on a boss 33 secured to the adjacent guide rail whereby the bar is constrained to partake of a substantially parallel motion when actuated by the rocker. This bar extends from the rocker arm 29 to a point close to the lower end of the path of travel of wing arm W at which the latter seats on the usual adjustable sill support X and as the bar lies between said path and the hatch way wall adjacent the door jamb, the wing arm when in transverse alignment with any part of it prevents the bar from being manually raised to swing the rocker on its pivot and the latter is thereby effectively locked against retraction except when the door is closed or substantially so and the wing arm thus cleared from transverse alignment with the bar. The bar when the door is open thus maintains the rocker substantially in the position illustrated in Fig. 3 and under these conditions, the rocker through engagement with pin 30 holds the lower latch arm 1 retracted and the latter projecting its dog 16 into the path of the tumbler 13 holds the upper latch arm 4 retracted even if the retiring or other cam normally so holding it be tampered with, and while these several parts are thus locked in position the switch in contact unit 20 also remains locked to prevent completion of a circuit through the main driving motor to move the elevator.

While the operation of the apparatus heretofore described may perhaps be understood without further explanation it may be noted that it requires no special attention from the elevator operator to insure proper performance of its functions as will be evident from a brief reference to the various conditions which arise automatically during the cycle comprising arrival of the elevator at the floor level, opening and closing of the door panels and departure of the elevator from the floor. Thus as the elevator approaches the floor level, the door panels P, P' and the interlock parts are in the several positions illustrated in Fig. 2. As previously mentioned the elevator may be equipped with a retiring cam or a stationary one, and substantially as it reaches floor level and is brought to a stop the cam, if of the former type is projected and engages roller 6 to actuate roller arm 5 and latch arm 4, or if the latter type likewise engages the roller and similarly actuates the roller and latch arms. In either case the tumbler 13 is simultaneously and automatically moved out of the path of dog 16 on latch arm 1, and if the cam is a retiring one the switch in contact unit 20 is thereupon actuated to hold the main circuit open.

The operator may now open the door by manipulating the usual handle, (not shown) connected through a draw bar B with the striker

cam 11 which can now swing the latch arm 1 out of the path of the wing arm W due to the tumbler having been cleared from the path of the latch dog 16. As the latch arm 1 moves, if the interlock is arranged for use with a stationary cam on the elevator the contact unit switch opens at this point rather than earlier in the cycle as it does when a retiring cam is used, and in either case as the door panels are moved in opposite directions, either mechanically or manually, the wing arm W moves the rocker 26 on its pivot to the position shown in Fig. 3 and through its subsequent alignment with the bar 31 maintains the rocker in position to keep the latch arm 1 retracted through engagement with the latch pin 30.

Thus the latch arm 1 cannot be moved manually towards the interior of the hatchway while the door remains open, and as the latch dog 16 therefore lies in the path of the tumbler 13 the upper latch arm 4 and the roller arm 5 are also held retracted, so the contact unit switch is kept open no matter which latch arm is rigid with the contact unit control fork 22, this depending, as noted, on whether a retiring or a stationary cam is used on the elevator to actuate the roller arm 5. When the doors are thereafter closed, as the wing arm W rises along the holding bar 31 and past the now retracted lower latch arm 1 it engages the upper arm 27 of the rocker 26 which was moved into its path by depression of the lower arm 29 when the door was opened, and as the wing arm clears the notch of the latch arm 1 the latter can swing to locking position beneath it.

If the elevator cam is a retiring one it is retracted in the normal way on actuation of the elevator control switch and this allows the roller arm 5 and latch 4 to move to locking position and thereby close the contact unit switch before the main driving motor is energized, usually by automatic mechanism with which the present invention is not concerned. If, however, a stationary cam is used the contact unit switch is closed simultaneously with the locking of the doors thus allowing the elevator to be operated, and as the said cam moves away from the roller 6 the upper latch arm 4 is restored to locking position to lock the upper door panel by engagement with lock bracket L. In either case the parts are thus restored to the positions shown in Fig. 2 with both door panels locked. As the main driving motor circuit is interconnected via armored cable C through contact unit 20 the switch in which is opened whenever the door is unlocked either accidentally or by design it is impossible for the elevator to be operated at any position in the hatchway except when all doors giving access thereto and provided with my interlock are closed and locked.

As my interlock is substantially a self contained unit which in itself embodies all the parts essential for securely locking the door panels when the latter are provided respectively with a locking bracket and a wing arm, or comparable latch engaging devices, it may be readily incorporated in existing elevator installations as well as in new ones during the course of their erection, the latches being adapted respectively for actuation in proper sequence by a retiring or stationary cam such as those long heretofore in use for operating door latches of various kinds and by a manually operated mechanical device of any suitable character, of which one is the striking cam 11, herein shown and described, to effect full release

of the panels, such cams or their equivalents however forming no part of the mechanism which actually locks the panels when closed.

Moreover as the parts are designed to afford adequate rigidity and strength with great durability the interlock, which may readily be incorporated in either old or new elevator installations, when once installed becomes a substantially permanent fixture normally requiring no attention except perhaps an occasional application of lubricant to its bearings to insure continuous service in the performance of its intended functions, while the safety it affords from the standpoint of both mechanical and electric controls meets the standards of the Underwriters Laboratories, required in many jurisdictions to permit erection and operation of elevators.

It will thus be apparent my interlock is adapted for use with biparting elevator doors of various types and in association with elevator installations of various kinds, and is effective to prevent abnormal operation of the elevator and access to the hatchway from a floor in the absence of the elevator without the slightest impairment of or interference with its normal operation.

While I have herein shown and described with considerable particularity certain embodiments of the invention and referred especially to their use in conjunction with vertically slideable biparting elevator doors such as are extensively used for freight elevators and the like it will be understood that the principles of the invention are applicable as well in other installations, particularly those in which positive control of an electric circuit in accordance with the positioning of a reciprocal element is required; therefore I do not desire or intend to limit or confine the use of the invention to biparting elevator doors, as other uses for mechanism conforming thereto, and changes and modifications in the form, construction and relationship of the several parts of that embodiment thereof herein disclosed will readily occur to those skilled in the art and may be made if desired, without departing from the spirit or scope of the invention as defined in the appended claims.

Having thus described my invention, I claim and desire to protect by Letters Patent of the United States:

1. An interlock for a pair of oppositely reciprocal sliding door panels comprising pivoted latch arms each adapted when in one position to lock one of the panels against movement in one direction, a tumbler actuated by one of the arms operative when the arms are in said position to inhibit movement of the other arm therefrom, and means carried by said other arm operative when the tumbler has been moved from its inhibiting position and said other arm moved from locking position to engage the tumbler to prevent its return to inhibiting position.

2. An interlock for a pair of oppositely reciprocal sliding door panels comprising pivoted latch arms each adapted when in one position to lock one of the panels against movement in one direction, interengageable means carried by the arms cooperative when the arms are in said position to inhibit movement of one of them therefrom in advance of the other and to restrain return of said other arm to locking position while the first arm remains out of said position.

3. An interlock for a pair of oppositely reciprocal sliding door panels comprising pivoted latch arms each adapted when in one position to lock

one of the panels against movement in one direction and movable about a common axis between locking and non-locking positions and means actuated by one of the arms when moved from locking to non-locking position operative when the arm is in the former position to inhibit movement of the other arm to non-locking position and operative when both arms are in the latter position to inhibit movement of the first arm to locking position.

4. An interlock for a pair of oppositely reciprocal sliding door panels comprising pivoted latch arms each adapted when in one position to lock one of the panels against movement in one direction and movable about a common axis between locking and non-locking positions, means actuated by one of the arms when moved from locking to non-locking position operative when the arm is in the former position to inhibit movement of the other arm to non-locking position and operative when both arms are in the latter position to inhibit movement of the first arm to locking position, and means actuated by one of the arms operative to interrupt an electrical circuit when said arm is moved from locking to non-locking position.

5. An interlock for a pair of oppositely reciprocal sliding door panels described comprising pivoted latch arms each adapted when in one position to lock one of the panels against movement in one direction and movable about a common axis between locking and non-locking positions, means actuated by one of the arms when moved from locking to non-locking position operative when the arm is in the former position to inhibit movement of the other arm to non-locking position and operative when both arms are in the latter position to inhibit movement of the first arm to locking position, and means engageable with one of the arms and with an element carried by the panel locking by said arm operative to hold the latter in non-locking position whenever said panel is in a position other than that in which it is disposed when locked by said arm.

6. In combination with an elevator, an actuating cam carried thereby, a biparting door comprising upper and lower vertically movable panels at an entrance to the elevator hatchway, a locking bracket projecting from and movable with the upper panel and a wing arm projecting from and movable with the lower panel, interlocking means comprising upper and lower latch arms respectively adapted to be engaged by the bracket and the wing arm when disposed in the paths thereof, a switch disposed adjacent the latch arms, means actuated by one of the latch arms for successively opening and closing the switch, a roller arm projecting from the upper latch arm adapted for engagement by the actuating cam to move said arm out of the path of the bracket and a tumbler depending from the upper latch arm effective when said arm is in said last mentioned path to inhibit movement of the lower latch arm out of the path of the wing arm and effective when the lower latch arm is out of the path of the wing arm to inhibit movement of the upper latch arm into the path of the bracket.

7. In combination with an elevator, an actuating cam carried thereby and a biparting door comprising upper and lower vertically movable panels at an entrance to the elevator hatchway, a locking bracket projecting from and movable with the upper panel and a wing arm projecting

from and movable with the lower panel, interlocking means comprising upper and lower latch arms respectively adapted to be engaged by the bracket and the wing arm when disposed in the paths thereof, a roller arm projecting from the upper latch arm adapted for engagement by the actuating cam to move said arm out of the path of the bracket, a tumbler depending from the upper latch arm effective when said arm is in said path to inhibit movement of the lower latch arm out of the path of the wing arm and effective when the lower latch arm is out of said last mentioned path to inhibit movement of the upper latch arm into the path of the bracket, and means interconnected with the lower latch arm operable when said arm is out of the path of the wing arm and the wing arm is out of the path of said latch arm to inhibit movement of the latter into the path of the wing arm.

8. In combination with an elevator, a biparting door comprising upper and lower vertically movable door panels at an entrance to the elevator hatchway, a locking bracket projecting from and movable with the upper panel, and a wing arm projecting from and movable with the lower panel, interlocking means comprising upper and lower latch arms respectively adapted to be engaged by the bracket and the wing arm when disposed in the paths thereof, means interconnecting the latch arms operative to inhibit their movements otherwise than in accordance with a predetermined cycle which, beginning with the latch arms disposed in positions respectively for engagement by said bracket and said wing arm includes successively movement of the upper latch arm out of the path of the bracket, movement of the lower latch arm out of the path of the wing arm, movement of the lower latch arm into the path of the wing arm and movement of the upper latch arm into the path of the bracket, and means for moving said latch arms sequentially out of the paths of the bracket and wing arm.

9. In combination with an elevator, an actuating cam carried thereby and a biparting door comprising upper and lower vertically movable door panels at an entrance to the elevator hatchway, a locking bracket projecting from and movable with the upper panel, a wing arm projecting from and movable with the lower panel, interlocking means comprising upper and lower latch arms respectively adapted to be engaged by the bracket and the wing arm when disposed in the paths thereof, means interconnecting the latch arms operative to inhibit their movements otherwise than in accordance with a predetermined cycle which, beginning with the latch arms disposed in positions respectively for engagement by said bracket and said wing arm, includes successively movement of the upper latch arm out of the path of the bracket, movement of the lower latch arm out of the path of the wing arm, movement of the lower latch arm into the path of the wing arm and movement of the upper latch arm into the path of the bracket, and means engageable with the wing arm for restraining movement of the lower latch arm into the path of the wing arm after it has been moved therefrom and the wing arm moved downward with the lower panel to a point below that occupied when the lower latch arm is in the path of the wing arm.

10. In combination with a slidable elevator door panel and a wing arm carried thereby, a pivoted latch arm projectible into and out of the path

of the wing arm when the panel is in closed position, a movable bar extending parallel to said path, pivoted links supporting the bar operative to maintain it in parallelism with said path during movement transversely thereof, and means projecting from the latch arm engageable by one of said links to maintain the latch arm retracted from the path of the wing arm when the bar has been moved in one direction transversely of said path, the wing arm when the panel is in open position lying adjacent said bar in a position to obstruct its corresponding movement in the opposite direction.

11. An elevator door interlock comprising movable latch arms respectively adapted in one position to lock one of the panels of a biparting elevator door when closed, and means interconnecting the latch arms operative to hold one arm in said position when the other arm is in the corresponding position and to hold said other arm in a different position when the first arm is in a correspondingly different position, said means comprising a latch dog movable with the first arm and a tumbler engageable by the dog pivoted to and movable with the second arm and disposed in the path of the dog when the arms are in said first position, said dog being disposed in the path of the tumbler when the arms are in the second position.

12. An elevator door interlock comprising movable latch arms respectively adapted to lock one of the panels of a biparting elevator door when closed, and means interconnecting the latch arms operative to hold one arm in locking position when the other arm is in the corresponding position and to inhibit the return of said other arm to locking position when said first arm is in non-locking position, said means comprising a latch dog movable with the first arm and a tumbler engageable by the dog pivoted to and movable with the second arm and disposed in the path of the dog when the arms are in said first position, said dog being disposed in the path of the tumbler when the arms are in the second position.

13. An elevator door interlock comprising movable latch arms for releasably holding closed the panels of a biparting elevator door, means interconnecting the latch arms operative to lock one

arm in position to so hold one panel when the other arm is in holding position with respect to the other panel, means for successively moving said last mentioned arm and then said first arm to other positions to release the panels and means carried by said last mentioned arm for holding it in said other position when the first arm is in its said other position.

14. An elevator door interlock comprising movable latch arms each adapted to releasably hold closed one of the panels of a biparting elevator door, means interconnecting the latch arms operative to lock one arm in holding position when the other arm is in corresponding position, means operable successively to move said other arm and then said first arm to non-holding positions and means for maintaining the first arm in its non-holding position while the corresponding door panel is open comprising a detent projecting from the arm, a pivoted lever engageable with said detent and means for actuating said lever.

15. In a door interlock for biparting elevator doors comprising opposed panels and means supported by each panel adapted to engage a latch, upper and lower latches respectively adapted for engagement by said means to lock the panels and interlocking means imposing a predetermined sequence of operations on the latches in the cycle of successively unlocking and relocking the panels, comprising a tumbler carried by one of the latches, and a latch dog carried by and movable with the other latch engageable with the tumbler to inhibit movement of the latter latch when the tumbler and latch dog respectively are in predetermined positions and to inhibit movement of the tumbler-carrying latch when the tumbler and dog respectively are in other positions.
